LAWRENCE H. HEUER, OF DETROIT, MICHIGAN, ASSIGNOR TO THE EVANS AUTO LOADING CO., INC., OF DETROIT, MICHIGAN

DEVICE FOR HOLDING VEHICLES

Application filed April 5, 1928. Serial No. 267,615.

This invention relates to device for holding vehicles and the like against movement during shipment, and has more particular reference to improved means for anchoring such devices upon the floors of freight cars or the like.

An important object of the invention is to provide a connection between the foot portion of the tie member of the device and its anchorage plate, that will prevent the foot portion from pulling loose from the anchorage plate when the device is subjected to strains and stresses.

Another object is to provide a device of this character that is extremely simple and durable in construction, and that can be economically and expeditiously manufactured.

I am aware of the fact that it has been heretofore proposed to connect the anchorage plate to the foot portion of a tie member by means of clip connections. In each case, however, the construction has been found unsatisfactory because the clips become loose, allowing the foot portion to be pulled loose from the anchorage plate.

I have overcome the above difficulties by providing the anchorage plate with a depressed strip-like portion forming a longitudinal slot in the anchorage plate and providing a longitudinal retaining loop on the bottom of said anchorage plate directly beneath said slot, extending the foot portion of the tie member through said loop transversely of and at the underside of said anchorage plate, and pressing the loop upwardly toward the plane of the anchorage plate to crimp a transverse part of the foot portion upwardly into the slot and firmly clamp the foot portion and anchorage plates together so that they will not pull apart when the holding device is subjected to strains and stresses. Moreover, this connection may be economically and expeditiously effected by the use of a conventional sheet metal cutting machine or press, thereby preserving the desirable low cost of production.

The invention resides in the novel features of construction, combination and arrangement of parts hereinafter more fully de-

scribed, shown in the accompanying drawing and claimed.

In the drawing:

Figure 1 is a side elevational view of a holdown device embodying my invention, 55 applied to a vehicle;

Figure 2 is a perspective view of the device;

Figure 3 is an enlarged fragmentary perspective view more clearly showing the manner of connecting the anchorage plate to the foot portion of the tie member; 60

Figure 4 is a bottom perspective view of the construction shown in Figure 3; and

Figure 5 is a section on line 5—5 of Figure 3.

The present device, which is adapted for holding a vehicle upon the floor of a freight car while in transit, is shown as preferably embodying a tie member 5 in the form of an inverted U-shaped loop having at its free ends the lateral foot portions 6 to which the anchorage plates 7 are secured. The loop 5 and anchorage plates 7 are preferably constructed of band iron, and the plates 7 have suitable openings 8 in the opposite end portions thereof for receiving securing elements, such as the nails 9. The anchor plates 7 cross the foot portions 6, and a plurality of spaced openings 8' are preferably provided in each anchor plate and are placed in registration with similar openings 8" provided in each foot portion 6 for receiving further securing elements similar to the nails 9.

As shown clearly in Figures 3 to 5 inclusive, each anchor plate 7 is provided with a central depressed strip-like portion to form a longitudinal elongated slot 10 in the anchor plate intermediate the openings 8' and of a length slightly greater than the width of the foot portion 6, and to provide a longitudinal retaining loop 11 on the underside of the anchor plate directly beneath the slot 10. The foot portion 6 is passed through the loop 11 and disposed transversely of and at the under side of the anchor plate 7 as clearly shown in the drawings, the foot portion 6 snugly fitting in the loop 11 to avoid, to a certain extent, turning or twisting of the foot portion relative to the anchor plates.

The loop 11 is then firmly pressed upwardly toward the plane of the anchor plate so that the intermediate part of the foot portion 6 is crimped transversely as at 12 upwardly into the slot 10. In this way the anchor plate is firmly clamped to the foot portion and mechanically locked thereon, by a permanent connection which effectively prevents the anchor plate and foot portions from being pulled apart when the device is subjected to stresses and strains. Moreover, turning or twisting of the foot portions 6 is effectively resisted so that tearing of the parts at the nail holes 8' and 8'' is positively prevented 15 for insuring that the device will remain operative for the purpose for which it is designed.

In operation, the loop portion 5 is disposed to straddle a spring, and axle or other suitable part of the vehicle, and the assembled 20 foot portions 6 and anchor plates 7 are fastened to the floor of the freight car by means of the nails 9 or the like driven through the openings 8 and the registered openings 8' and 8''.

From the above description, it is believed 25 that the construction and advantages of the present invention will be readily understood, it being apparent that the number and position of the nail holes may be varied within 30 the scope of the appended claims.

What I claim as new is:—

1. A device of the class described comprising a tie member having a leg portion, a substantially flat foot portion projecting from the lower end of said leg portion, a substantially flat anchorage member crossing said foot portion and having lateral extensions projecting beyond opposite sides of said foot portion and provided with apertures for receiving securing elements, said anchorage member having a depressed portion forming a retaining loop through which said foot portion extends and provided with a slot above said loop, said foot portion having a transverse part crimped upwardly into said slot and having said loop clamped against said crimped part thereof.

2. In a device of the class described, the combination with a tie member having an upwardly standing leg portion and a substantially horizontal foot portion, of an anchorage plate provided with openings adapted to receive securing elements and having a retaining loop struck downwardly therefrom to provide a slot in the anchorage plate above said loop, said foot portion extending through said loop and having a part clamped between the loop and the bottom of the anchorage plate and crimped upwardly into said slot.

3. A hold-down device comprising a strap iron tie member having upright leg portions and lateral foot portions, and a strap iron anchorage plate crossing each foot portion and having openings to receive securing elements, each anchorage plate having a por-

tion struck downwardly therefrom to provide a slot and a loop below the slot through which the associated foot portion extends, said loops being pressed against the foot portions to clamp the anchorage plates thereon, and said foot portions being transversely crimped upwardly into the slots of the anchorage plates.

4. A device of the class described comprising a tie member having a leg portion, a substantially flat foot portion projecting from the lower end of said leg portion, a substantially flat anchorage member crossing said foot portion and having lateral extensions projecting beyond opposite sides of said foot portion and provided with apertures for receiving securing elements, said anchorage member having a depressed portion forming a retaining loop through which said foot portion extends and provided with a slot above said loop, said foot portion having a transverse part crimped upwardly into said slot and having said loop clamped against said crimped part thereof, said anchorage member and foot portion having further aligned pairs of openings at opposite sides of the loop to receive further securing elements.

In testimony whereof I affix my signature.
